TABLE CLOTH

Yasuhiro Oshima, Osaka, Japan, assignor to Meiya
Gravure Chemical Co., Ltd., Osaka, Japan, a corporation of Japan

Filed June 23, 1965, Ser. No. 85,856

Term of patent 3½ years

(Cl. D92—26)

FIG. 1

FIG. 4

FIG. 1 is a plan view of a table cloth showing my new design;

FIG. 2 is a modified form of the design shown in FIG. 1;

FIG. 3 is another modified form of the design shown in FIG. 1; and

FIG. 4 is a third modified form of the design of FIG. 1.
I claim:

The ornamental design for a table cloth, as shown and described.
